DESIGN FOR A MEDICINAL AND DENTAL PROPORTIONING AND MIXING APPARA- TUS

John J. Curry, Philadelphia, Pa.

Application November 7, 1947, Serial No. 142,380

Term of patent 14 years

(Cl. D24—1)

To all whom it may concern:

Be it known that I, John J. Curry, a citizen of the United States, residing at Philadelphia, in the county of Philadelphia, State of Pennsylvania, have invented a new, original, and ornamental Design for a Medicinal and Dental Proportioning and Mixing Apparatus, of which the following is a specification, reference being had to the accompanying drawing, forming part thereof.

Figure 1 is a front elevation of the medicinal and dental proportioning and mixing apparatus, showing my new design;

Figure 2 is a side view thereof;

Figure 3 is a top view thereof; and

Figure 4 is a rear view.

I claim:

The ornamental design for a medicinal and dental proportioning and mixing apparatus, substantially as shown.

JOHN J. CURRY.
